UNITED STATES PATENT OFFICE.

WILLIAM FOSTER MERRILL, OF NEW YORK, N. Y.

ELECTRIC STOVE.

1,134,886.

Specification of Letters Patent.

Patented Apr. 6, 1915.

Application filed July 10, 1914. Serial No. 850,277.

To all whom it may concern:

Be it known that I, WILLIAM FOSTER MERRILL, a citizen of the United States, residing at New York, in the county of New York and State of New York, have invented certain new and useful Improvements in Electric Stoves; and I do hereby declare the following to be a full, clear, and exact description of the invention, such as will enable others skilled in the art to which it appertains to make and use the same.

This invention relates to new and useful improvements in heating elements for electric heaters, and has for its principal object 15 to provide a device in which the heating elements are interchangeable.

Another object of the invention is to provide a novel heating element provided with a plurality of removable tablets so that should any of the wires become broken or otherwise inoperative, a new coil may be substituted.

A further object of the invention is to provide a novel means for insulating the wires from each other to prevent the device from becoming short circuited.

With these and other objects in view, the invention consists in the novel combination and arrangement of parts which will be 30 fully set forth in the following specification and accompanying drawings, in which,

Figure 1 is a perspective view of a heating element constructed in accordance with this invention, Fig. 2 is an end view in elevation thereof, Fig. 3 is a detail perspective view of one of the tablets carrying the wires, Fig. 4 is an enlarged detail sectional view of a fragment of the tablet illustrating the method of securing the same on the base portion, and Fig. 5 is a detail view of the wiring circuit.

Referring now to the drawings by characters of reference, the numeral 1 designates the base portion of the device which comprises the plate 2 which is preferably of slate or a similar material. This plate is provided with the mica plates 3, which cover the faces of the plate 2 and form an insulating heat-resisting cover therefor. This base portion 1 is bored at suitable intervals and arranged to receive the upstanding cylindrical members 4, which are threaded near their lower terminals to receive the nuts 5, between which the base portion is 55 clamped.

The heating tablets which are best illus-

trated in Fig. 3, are designated generally by the numeral 6, and comprise the plate 7 of slate or similar material, which is covered with the mica or similar cover 8. Each of these tablets is bored near its ends as at 9 and is arranged to receive the bolt 10, which is held in place by means of the nut 11. This bolt is arranged to clamp the plates 13 to the tablets 6 to form the electrical connection for the resistance wire 14 which is wound on the plate and connected as illustrated in Fig. 3. Each of these plates 13 is bent outwardly near its free terminal as at 15, so that the same may coöperate with the opposite plate in clamping the posts 4 when the device is in place.

Secured to the centermost post 4 near one of the lateral extremities are the plates 16 which are bent upwardly as illustrated in Fig. 1 and outwardly to form the terminals by which the device is connected to an electric circuit.

Referring to the wiring diagram it will be apparent that the terminals 16 connect to the central posts on one side and the central posts on the opposite side are connected in any suitable manner with the next adjacent post as at 17. The adjacent posts on the opposite side are then connected to the end posts as at 18, and the opposite end posts are connected together as at 19, thus completing the circuit through the heating device when the several coils, designated generally by the numeral 20, are in place.

It will be apparent from the foregoing that in use, the several tablets carrying the heating coils are set on their respective posts so that the clamps formed by the plates 13, frictionally engage the posts 4, thereby forming a connection between the oppositely disposed posts. The device is then connected in circuit through the means of the terminals 16 and when the current is thrown on, the same will pass through the terminals and into the heating coils as shown in Fig. 5. It will thus be seen that the coils will be heated through the passing of the current therethrough, and should anyone become inoperative, it may be easily and quickly removed and a new one placed thereon or the original repaired without the necessity of disturbing the remaining coils.

While in the foregoing there has been shown and described the preferred embodiment of this invention, it is to be understood that such changes may be made in the

combination and arrangement of parts as will fall within the spirit and scope of the invention, as defined in the appended claim.

Having thus described my invention, I claim:

An electric heater for stoves comprising a base plate, said base plate having a plurality of apertures in its sides adjacent to its marginal edge, a plurality of conducting pins extending through said apertures and secured therein, wire holding tablets disposed between said conducting pins, clamping plates secured centrally at each end of

said tablets, their free ends bent to conform to the shape of the pin and clamped thereon, means for connecting the pin and tablets in series with an electric current, and a plurality of heating coils removably secured to the tablets and clamping plates.

In testimony whereof I affix my signature in presence of two witnesses.

WILL F. MERRILL.
